United States Patent Office

Des. 176,939
Patented Feb. 21, 1956

176,939

TEXTILE FABRIC OR SIMILAR ARTICLE

Sergei Bogdanovich, Carmel, N. Y., assignor to Weil & Durrse, Inc., New York, N. Y., a corporation of New York

Application May 19, 1955, Serial No. 36,107

Term of patent 3½ years

(Cl. D92—1)

FIG. 1

Fig. 1 is a face view of a textile fabric or similar article, showing my new design. The full width of the fabric is disclosed horizontally and the design unit is repeated vertically in proper relation to complete the fabric.

Fig. 2 is an enlarged face view thereof, of the portion of Fig. 1 which is enclosed in dot and dash lines.

I claim:

The ornamental design for a textile fabric or similar article, as shown and described.
